CLAIM

The ornamental design for a file, as shown and described.

DESCRIPTION

FIG. 1 is a perspective view of a file showing my design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The filing surface has been fragmentarily in FIGS. 1, 4
and 5 for ease of illustration.

FIG. 2

FIG. 3

FIG. 4

FIG. 5

FIG. 6

FIG. 7
